UNITED STATES PATENT OFFICE.

WILLIAM M. MACKAY, OF EAST ORANGE, NEW JERSEY.

SECTIONAL BOILER.

1,306,675.

Specification of Letters Patent. Patented June 10, 1919.

Application filed August 3, 1917 Serial No. 184,223.

To all whom it may concern:

Be it known that I, WILLIAM M. MACKAY, a citizen of the United States, residing at 73 Warrington Place, East Orange, county 5 of Essex, and State of New Jersey, have invented certain new and useful Improvements in Sectional Boilers, fully described and represented in the following specification and the accompanying drawings, forming 10 a part of the same.

This invention relates to a boiler having a base containing an ash-pit section and provided with a grate upon the top, the boiler being formed of sections which form a central 15 magazine with water-space surrounding the sides and top of the same, with a water-leg surrounding the firebox, and a shoulder extended from the bottom of the magazine to the water-leg parallel with the grate, a combustion-chamber above the magazine, fire-tubes extended through the water-space around the magazine from the shoulder to the combustion-chamber, a smoke-chamber adjacent to such combustion-chamber, and a deflector between the two chambers with an opening for the indirect movement 20 of the gases from the fire-tubes through the combustion-chamber to the smoke-chamber.

These features are obtained by making the firebox section to extend above the top of the magazine and recessed in said top to form the lower part of the combustion-chamber; by making the deflector-section 35 with recess upon its under side forming the upper part of the combustion-chamber and a recess upon its upper side forming the lower part of the smoke-chamber, and a dome-section with recess upon its lower side

40 to form the upper part of the smoke-chamber. The deflector-section is formed with a water-plate with notch in one edge through which the smoke passes from the combustion-chamber to the smoke-chamber, and an opening is extended to the outside of the boiler from the combustion-chamber and from the smoke-chamber below and above this notch so that a door applied to the said opening overlaps the sections above and below the opening, and gives full access to both these chambers for cleaning out the same. The shallowness of the recesses facilitates 45 the casting of the sections.

The fuel may be burned with either an upward or downward draft, as the upward 55 draft is produced by closing the bevel-flap on the door of the magazine and opening the bevel-flap on the door in the ash-pit, so that air passes upward through the grate and the products of combustion move wholly 60 upward through the fire-tubes.

Upon the contrary, the closing of the ash-pit bevel-door and the opening of the magazine bevel-door causes the draft to move downwardly through the fuel in the magazine 65 and then upward through the fire-tubes without passing through the grate.

The invention will be understood by reference to the annexed drawing, in which Figure 1 is a vertical section taken at the 70 center line of Fig. 2; Fig. 2 is a vertical section taken at the center line of Fig. 1 with the top section formed as a steam-dome; Fig. 3 is a plan of the firebox section of Fig. 1; Fig. 4 is a plan of the middle or 75 deflector section, of Fig. 1; and Fig. 5 is a plan of a firebox of alternative shape.

The boiler is shown formed with an ash-pit section, a fire-box section A', a deflector section B' and a dome section C'. 80

The fire-box section is set upon a base D having a grate E and an ash-door E', and this section, as shown in Fig. 3, has a circular magazine G' from which a doorway E² extends to the outer side of the section. 85

A horizontal shoulder *j* is shown extended from the bottom of the magazine to an annular water-leg *a*⁴. The water-leg forms the periphery of the fire-box and extends below the shoulder upon the magazine, and the fire-tubes *a*² are extended upwardly from such shoulder through the water-space between the wall of the magazine and the outer shell of the section, as shown in Fig. 3.

A combustion-chamber *f'* is formed in the 95 top of the section A', as shown in Fig. 3, over the magazine and over the tops of the fire-tubes, with which it has open connection.

The deflector section B' is formed, as 100 shown in Figs. 2 and 4, of a water-plate or disk having a smoke-chamber *h*² in the top, and a notch *B*² cut out of one edge, as shown in Fig. 2, to permit the passage of the gases from the combustion-chamber *f'* 105 to the smoke-chamber *h*².

The notch is so arranged as to drive the gases from the rear to the front portion of the deflector section, thus retaining them longer in the combustion-chamber to fully 5 complete their combustion.

5 A damper-box *r* is attached to the outlet *m'* of the smoke-chamber, and is provided on the top of a collar for the smoke-pipe *s²* and at the outer end with a hinged check-damper *t*.

10 An auxiliary or throttling damper *u* is hinged within the box adjacent to the outlet *m'* and proportioned to close about three-quarters of the passage in the damper-box 15 when this damper is drawn across said passage.

15 The two dampers are connected by a link *v* which holds the damper *u* entirely open when the damper *t* is closed, and when the 20 check-damper is open, the link draws the damper *u* across the passage, and thus greatly checks the escape of gases, while it permits a sufficient escape to prevent back-draft of such gases from the furnace.

25 The doors *E'* and *E²* have hinged flaps *d⁴* and *d⁵* to admit air when desired; and when the air is admitted at the ash-door and the fuel-door is closed, the draft is upward through the grate; but when the magazine 30 is nearly filled with fuel and the ash-door wholly closed, the flap on the door *E²* may be opened more or less, and the draft passed downward through coal in the magazine to the fire-tubes.

35 In Figs. 1 and 2, a drop-flange *s* is shown extended downward from the inner corner of the shoulder *j*, to guard the bottoms of the fire-tubes from any crowding of coal into the tubes.

40 With this construction, the coal flowing down from the magazine slants laterally downward from the flange, and forms an annular combustion-space at the bottoms of the fire-tubes, which greatly promotes the 45 combustion of the fuel, while it wholly prevents any obstruction of the fire-tubes by the coal.

The construction furnishes a very free and unobstructed passage for the water, 50 from the inlet at the water-leg around the fire-space to the outlet at the top, and thus secures the free circulation that is desired in such a boiler.

55 In practice, the outsides of all the sections are coated or clothed with asbestos or other non-heat-conducting jacket, but this is not shown in the drawing, as it would obscure the actual construction, and forms no part of the present invention.

60 The firebox section shown in Fig. 5 is of rectangular form and exactly of the same diameter as that shown in Fig. 3, but has a greater periphery and a greater area, while it occupies in practice no more room or floor-

space than the circular firebox. It thus affords room for more fire-tubes, and permits the spacing of such tubes farther apart to secure a freer circulation of water. I have therefore claimed the rectangular form on account of its advantages.

70 I claim—

1. A steam or hot-water boiler formed of four sections with horizontal joints, comprising a base with grate thereon, a firebox section having a central magazine with water-space surrounding the sides and top of the same and having the lower part of the combustion-chamber recessed in the top of the section, a water-leg extended downward below the bottom of the magazine, fire-tubes 80 extended through the water-space from the said fire-box upward into the combustion-chamber, a deflector-section formed of a water-plate recessed upon the under side to form the upper part of the combustion-chamber and having a notch in one edge for the upward passage of the gases, the periphery of the notch being entirely surrounded by space filled with water to absorb heat from the gases passing through 90 such notch, and a dome-section fitted to the top of the deflector-section with their adjacent surfaces recessed to form a smoke-chamber, and a smoke-outlet extending from such chamber through the wall of the section. 95

2. A steam or hot-water boiler formed of four sections with horizontal joints, comprising a base with grate thereon, a firebox section having a central magazine with water-space surrounding the sides and top of the same and having a combustion-chamber recessed in the top of the section, water-tubes extending through the water-space around the magazine from the firebox into 105 the combustion-chamber, a deflector-section formed of a water-plate having a recess in its under side forming the top of the combustion-chamber and a recess in its upper side forming the bottom of the smoke-chamber, 110 and having a notch in one edge for the upward passage of the gases, and a dome-section fitted to the top of the deflector-section and having a recess upon its under side forming the top of the smoke-chamber, a 115

cleaning opening extended laterally from the combustion-chamber and smoke-chamber to the full depth of the same, and a cleaning-door fitted to said opening and overlapping, upon its upper and lower edges, the sections above and below the smoke-chamber and combustion-chamber so as to uncover both when the door is opened.

3. A steam or hot-water boiler formed of superposed horizontal sections and having a 125 firebox section of rectangular shape with a firebox in the bottom, a rectangular magazine closed at the top and smaller than the

fuel-space extended upwardly therefrom, a shoulder extended horizontally around the bottom of the magazine to the water-leg, a combustion-chamber above the top of such 5 magazine and a straight row of tubes upon each of three sides of the section extended upwardly from the shoulder to the said combustion-chamber, the fourth side of the sec-

tion having a doorway and door connected with the fuel-space in the bottom of the section, and a doorway and door connected with the magazine near the top of the section. 10

In testimony whereof I have hereunto set my hand.

WILLIAM M. MACKAY.
